MEANS FOR LAUNCHING TORPEDOES.

1,320,659.

Specification of Letters Patent. Patented Nov. 4, 1919.

Application filed December 9, 1918. Serial No. 265,917.

To all whom it may concern:

Be it known that I, TOM THORNYCROFT, a subject of the King of Great Britain and Ireland, residing at Westminster, England, 5 have invented Improvements in Means for Launching Torpedoes, of which the following is a specification.

This invention has reference to means for launching torpedoes by the expansion of 10 gases produced by the combustion of a suitable propellant or explosive in a separate chamber to the gun barrel. In means for this purpose as heretofore proposed, the breech end of a torpedo launching cylinder 15 has in some cases been adapted to form a combustion chamber and in others the combustion chamber has been made as a separate structure from the gun barrel itself and provided with a socket for the reception of 20 the charge of propellant or explosive, but none of such arrangements have been adapted to admit of the production of high pressure gases of several times the pressure 25 of the gas to be utilized in the torpedo launching cylinder itself and which shall also be comparatively high, say of the order of from one-quarter to one-half of a ton to the square inch.

In a separate explosion chamber of considerable volume, propellants, such as cordite, cannot be relied upon to burn uniformly and completely unless special provision is made to burn them in a chamber or container (hereinafter called a charge container) at pressures considerably in excess 30 of the pressure required in a separate gas receiver into which the gases pass and whence they pass to the torpedo launching cylinder. The mode of loading the charge 35 container with the explosive or propellant (hereinafter referred to as cordite) to insure proper and complete combustion thereof, is of importance, but the exact arrangement of the holes or passages in the wall 40 of the charge container through which the resultant gases of combustion pass to the gas receiver is of great importance in order that the combustion of the cordite shall 45 take place under the best conditions. For example, if the holes or passages are placed 50 only at the end of the charge container away from the point of first ignition, the flame resulting from the first ignition of the cordite will have to pass through all the rest 55 of the charge before the resultant gases can

find their way out through the holes and, consequently, much more rapid combustion of the charge will take place than is desirable, resulting in considerable shock.

Now the present invention has for its 60 object, *inter alia*, to provide a charge container wherein a charge of cordite can be burnt under very high pressure, say of the order of several tons to the square inch, and the resultant gases can be admitted to 65 a gas receiver wherein the gas will be maintained at a lower but still high pressure, say of the order of about two tons to the square inch and from which they can be delivered to the torpedo launching cylinder at a still 70 lower but comparatively high pressure, say of the order of from about one quarter of a ton to one half of a ton to the square inch. It also has for its object to admit of a 75 charge of cordite being burnt in a comparatively slow manner so as to avoid excessive shock.

To admit of a charge of cordite being burnt at a high pressure for the purpose set forth, the charge container is made of 80 comparatively small internal capacity to suit the charge of cordite to be burnt and it is provided with a gas outlet that will admit of the gases of combustion passing from the ignition end of the container to 85 the gas receiver and which is made of comparatively small cross sectional area and such as to enable the desired pressure to be set up in the charge container. To admit of the charge of cordite being burnt under high 90 pressure as set forth and in a comparatively slow manner, the charge container is provided with a gas outlet consisting preferably of a number of small holes or passages through which the resultant gases pass to 95 the gas receiver on their way to the torpedo launching cylinder, such holes or passages being arranged in such a manner that when the cordite begins to burn, the gases will first pass out from the container through 100 holes or passages that are near to the point where the charge is first ignited and then through succeeding holes. For this purpose the holes may be arranged at intervals along the length of the charge container 105 from the forward end thereof near to the point of ignition of the cordite charge.

The cordite container may conveniently be in the form of a cylinder projecting into the gas receiver, or part thereof, and be 110

formed with a number of small gas exit apertures arranged along its length and of small collective cross sectional area as set forth. Satisfactory results, for the purpose 5 of launching a torpedo as hereinafter described, can be obtained by providing such a container, adapted to carry a charge of about three and a half pounds of cordite, with about fifty-six apertures each of about 10 one-quarter of an inch in diameter, the total cross sectional area being thus about two and three quarter square inches. The cordite may be placed loose in the container, or it may be made up as a cartridge that is 15 inserted in the container. In each case, the cordite container is not of much larger internal capacity than the volume of the cordite charge to be employed, and is made of sufficient thickness and strength to withstand 20 the high pressure set up therein by the burning of the cordite charge. The resulting gases under pressure pass into and are collected in the gas receiver whence they pass through a restricted outlet, which may 25 be constituted by the perforations of a plate or baffling device of known kind, or by a pipe or passage of small bore, or by equivalent pressure reducing means, to the breech end of the torpedo launching cylinder and 30 be therein utilized to operate a ram or piston for launching a torpedo.

By the means described, a charge of cordite can be burnt in a more definite and complete manner and slower than has herein 35 tofore been practicable, to produce gases under very high pressure with little shock, and such gases can be utilized at a much lower pressure in a torpedo launching cylinder for launching a torpedo with a 40 comparatively low but still high and steady pressure and with greater accuracy than has previously been found practicable with torpedo launching cylinders as heretofore operated by gases under pressure.

45 The torpedo launching cylinder is fitted with a ram or piston the outer end of which, beyond the outer free end of the cylinder, is adapted to fit against the nose or stern of a torpedo, the cylinder being adapted to 50 cushion the ram or piston when it is near the outer end of its stroke. The internal diameter of the cylinder is much smaller than that of the torpedo to be launched so that the pressure of the gases admitted to 55 the cylinder is well maintained during the launching of a torpedo.

The combined cordite container and gas receiver can be variously constructed and arranged in relation to each other and to 60 the torpedo launching cylinder.

In the accompanying illustrative drawings, Figures 1, 2, 3, and 4, are central vertical sections, showing, diagrammatically, various constructions and arrange-

ments of torpedo launching apparatus according to the present invention.

In these examples, *a* is the gas receiver provided with or having in connection therewith, a charge container *b* constructed as hereinbefore described for the purpose 70 set forth and adapted to hold a charge of cordite, or an ordinary cordite cartridge, *c* is the torpedo launching cylinder into one end of which the gases under pressure produced by the combustion of the cordite 75 charge or cartridge flow from the gas receiver *a* through a perforated baffling device *d*, or equivalent pressure reducing device, whereby their pressure is reduced to the desired degree before entering the tor- 80pedo launching cylinder.

In the example shown in Fig. 1, the gas receiver *a* is of spherical shape and is connected to one end of the torpedo launching cylinder *c*, conveniently by screwing it to 85 a junction piece *c*¹ that has a hole *c*² of small cross sectional area extending therethrough and is screwed into the said cylinder. The charge container *b* is in the form of a perforated cylinder screwed into one 90 side of the gas receiver *a* and adapted to receive a charge of cordite, the total cross sectional area of the holes in such cylinder being comparatively small as and for the purpose hereinbefore set forth. *e* is a firing 95 device of any known or suitable kind, percussive or electric, carried by the charge container *b* and adapted to ignite the charge and capable of being operated directly by hand, or from a distance, as through a lan- 100 yard or electric conductors. In the example now being described, the charge container *b* is provided with a shoulder at *b*¹ to hold a percussion cap or detonator for igniting the charge in the container *b*. The baffling 105 device *d* is in the form of a perforated thimble screwed into the gas receiver *a* and in communication with the bore of the tor- 110pedo launching cylinder *c* through the hole *c*² in the junction piece *c*¹.

According to the constructions shown in Figs. 2 and 3, the gas receiver *a* with charge container *b* and baffling device *d* is arranged separately from the torpedo launching cylinder *c*. In such cases the gas 115 receiver *a* with associated parts may be arranged in proximity to and be carried by suitable supports *a*² independently of the torpedo launching cylinder *c* and be connected to the inlet end of such cylinder by 120 a straight pipe *h* and the perforated junction piece *c*¹, as shown in Fig. 2. Or it may, as shown in Fig. 3, be carried sidewise of the said cylinder *c*, as for instance below the cylinder as shown, as by supports *a*² on 125 such cylinder, and be connected by a bent pipe *h*¹ and the perforated junction piece *c*¹ to the inlet end of the cylinder.

Fig. 4 shows an arrangement similar to that shown in Fig. 3 but wherein the gas receiver is made in two parts *a* and *a*¹ connected by the pipe *h*², the part *a* carrying the charge container *b*, and the part *a*¹ being connected direct to one end of the torpedo launching cylinder *c* through the junction piece *c*¹.

m is a piston fitting the torpedo launching cylinder *o*, and *n* is its rod, which protrudes beyond the fore end of the cylinder and is adapted to act against a torpedo for launching it. For this purpose the outer end of the rod *n* is provided with a bell head *o* adapted to fit over and against the head of a torpedo *p* (Fig. 1) for the purpose of launching the torpedo stern first. The head *o* is made of sufficient dimensions to avoid any possibility of its acting against the firing pistol or equivalent carried by the head or nose of the torpedo. Or the head *o* may be adapted to act against the stern of a torpedo when it is desired to launch the torpedo head first. As will be seen, the internal diameter of the torpedo launching cylinder *c* is much less than the diameter of the torpedo *p* to be launched as and for the purpose hereinbefore mentioned. When the piston *m*, under the action of the gases under pressure admitted to the rear end of the cylinder *c* has traversed nearly the entire length of the cylinder, the gases are permitted to escape laterally through holes at *r* in the cylinder and the piston is brought to rest by cushioning on the air trapped in the closed end portion of the cylinder beyond these holes.

The operation of the torpedo launching apparatus is as follows:—

A cordite charge or cartridge is placed in the charge container *b* and the firing gear *e* fixed in place. When it is desired to discharge the torpedo, the firing gear is operated in the usual way by means of a lanyard or other device and the cordite charge or cartridge is then ignited. As the exit of the resulting combustion gases from the charge container *b* is restricted, as hereinbefore described, the cordite burns completely under high pressure and with little shock. The resulting gases are collected in the gas receiver *a* and thence pass through the hole or holes of the perforated baffling device *d* and also, it may be through the pipe *h*, *h*¹ or *h*², if used, or equivalent pressure reducing means into the torpedo launching cylinder *c* with practically no shock but with a comparatively low and steady pressure, where, acting on the piston *m*, the piston and its rod *n* are forced outward and the torpedo *p* launched from the boat to which the launching apparatus is fitted.

By means of the invention the use of air compressors and large air receivers is ob-

viated; also, as a consequence thereof, apparatus according to the invention is of comparatively small weight so that a small motor boat, say thirty to fifty feet long, can be adapted to carry and launch a torpedo of ordinary size.

What I claim is:—

1. Means for launching torpedoes by gases produced under pressure by the combustion of a propellant in a separate charge container and admitted at a lower pressure to the breech end of a torpedo launching cylinder, comprising, in combination, a charge container of comparatively small internal volume, a gas receiver of larger internal volume than the charge container and in communication therewith through a gas outlet that is made of comparatively small cross sectional area such that a charge of cordite or like explosive can be burnt in the container at a high pressure and in a uniform and complete manner, to produce, under high pressure, gases that pass into the gas receiver, a torpedo launching cylinder into which the gases flow from the gas receiver at a reduced pressure, and a piston arranged to work in said cylinder and having a rod or extension the outer end of which, beyond the outer end of the cylinder, is adapted to fit against the nose or stern of a torpedo, and means adapted to cushion the piston when the same is near the outer end of its movement.

2. Torpedo launching means according to the preceding claim, wherein the charge container comprises a chamber that is arranged to project into the gas receiver and is formed along its length with a number of small exit apertures the collective cross sectional area of which is small, as set forth, the apertures commencing near to the forward end of such container, substantially as described for the purpose set forth.

3. Torpedo launching means according to claim 1, wherein the rod or extension of the piston works in a fluid tight manner through the outer end of the torpedo launching cylinder and the cylinder is provided toward its outer end with lateral holes through which the impelling gases can escape when the piston moves beyond them, the portion of the cylinder between its outer end and the lateral holes serving as an air cushioning cylinder for the piston.

4. Torpedo launching means according to claim 1, wherein the cordite container, having a contracted gas outlet as set forth, is carried by a gas receiver that is in communication with the breech end of the torpedo launching cylinder through a passage of restricted cross sectional area.

5. Torpedo launching means according to claim 1, wherein the cordite container, having a contracted gas outlet as set forth, is

carried by a gas receiver connected to the breech end of the torpedo launching cylinder by a piping of restricted cross sectional area.

5 6. Torpedo launching means according to claim 1, wherein the gas receiver is made in two parts connected together by piping, one of such parts carrying the charge container

and the other being connected to the breech end of the torpedo launching cylinder 10 through a passage of restricted cross sectional area.

Signed at London, England this thirteenth day of November 1918.

TOM THORNYCROFT.
